RETAINER WIRE FOR THREAD GUIDES

Peleg B. Briggs, Ashway, R. I., assignor to The Atwood Machine Company, Stonington, Conn., a corporation of New Jersey

Application July 31, 1937, Serial No. 156,701

4 Claims. (Cl. 242—157)

This invention relates to retaining means for thread guides usually of porcelain and used extensively in thread twisting and winding machines.

More particularly the invention relates to means for fastening the wires forming the retaining means on to the traverse bar of the winding or twisting machine.

An object of the present invention is to provide a simple, inexpensive and easily attached retainer that will enable a porcelain or other form of thread guide to be resiliently retained in adjusted position so that the guide may be readily positioned on or removed from the traverse bar.

Another object of the invention is to so fasten the retainer wire to the traverse bar that the same pressure will be applied to adjacent guides, the opposite ends of which are retained by the oppositely extending ends of one retainer wire.

One feature that enables me to obtain the above objects is that a loop formed in the retainer wire is set into a deep longitudinal groove formed vertically in the traverse bar, there being a transverse screw through the bar intersecting the groove and disposed above the loop formed in the retainer wire, the loop entering the groove and extending below and around the screw so that the wire may tilt to any oblique position while being always disposed longitudinally and vertically in the traverse bar.

With the above and other objects in view, the invention includes the features of construction and operation set forth in the following specification and illustrated in the accompanying drawing.

In the accompanying drawing annexed hereto and forming a part of this specification, I have shown the invention designed for embodiment in a conventional form of textile winding machine but it will be understood that the invention can be otherwise embodied and that the drawing is not to be construed as defining or limiting the scope of the invention, the claims appended to this specification being relied upon for that purpose.

In the drawing:

Fig. 1 is a fragmentary front elevation of a traverse bar having the present guide retaining means applied thereto; and;

Figs. 2 and 3 are transverse sectional views taken respectively upon the planes of lines 2—2 and 3—3 in Fig. 1.

In the above mentioned drawing, there has been shown but one embodiment of the invention which is now deemed preferable, but it is

to be understood that changes and modifications may be made within the scope of the appended claims without departing from the spirit of the invention.

Briefly and in its preferred aspect the invention may include the following principal parts: first, a traverse bar having a deep but narrow longitudinal slot cut vertically into its upper edge or surface; second, an elongated wire having a central loop entering the groove and having its ends extending above the bar in opposite directions; and third, a transverse member such as a screw intersecting the groove and retaining the loop of the retainer against removal but permitting freedom of oblique movement in a vertical plane.

Referring more in detail to the figures of the drawing there is shown one end of a traverse bar 10 of a usual or conventional form used in textile machines. Positioned along this traverse bar 10 are a number of guides 11 usually of porcelain equally spaced along the bar. Each of the guides 11 is provided with a thread notch 12 of the usual form and in the upper surface is cut or formed a shallow longitudinal groove 13.

The retainer wire 14 for the guides 11 is bent as shown in Fig. 1 to form a central depending loop 15 and providing oppositely extending resilient arms or ends 21 extending therefrom. These ends 21 enter the grooves 13 of adjacent guides 11 and force the guides against the surface of the bar 10 and thus retain the guides in position. Each retainer wire 14 has its loop 15 disposed within a vertical longitudinally extending groove 16 formed in the traverse bar 10. The groove 16 is wide enough only for the diameter of the wire 14 so that the retainer is maintained in a vertical plane.

To retain the wire 14 in place but to permit tilting movement to equalize the pressure exerted by the ends 21 on the guides 11 a single member 17 is used. This retaining member 17 may preferably be in the form of a screw disposed transversely of the bar 10 and intercepting the narrow groove 16 at a point above the loop 15.

For the end guide 11 a special retainer wire is made use of for engagement with one side as shown in Fig. 1. This wire 18 may be formed as shown having one end shaped to correspond to ends 21 and to fit the groove 13 within the guide 11. The opposite end of the wire 18 enters the groove 16 and is looped as shown at 19. A screw 20 is disposed transversely of the traverse

bar 10 similarly to screws 17 and preferably passes within the loop 19.

Both forms of retainer wires 14 and 18 have their loop and end portions so formed that all parts of the wires lie in a single plane. The wires therefore require minimum bending operations and may be completely formed in a single operation.

I claim as my invention:

- 10 1. A retainer for thread guides comprising in combination a traverse bar having a longitudinal groove formed therein, thread guides mounted thereon, a wire having a central open loop adapted to enter the groove in said bar, oppositely extending end portions of said wire resiliently engaging against the upper surfaces of and holding adjacent guides on said bar, the entire length of said retainer being substantially in a single plane. and a holding member for said wire extending 15 transversely through the bar, intercepting said groove and passing freely through said loop.
- 20 2. A thread guide for textile machines comprising in combination a traverse bar having a narrow vertical groove extending longitudinally therein, thread guides resting on said bar, wire 25 retainers for said guides having a looped portion therein and having their ends resiliently engaging against the upper surfaces of adjacent guides, the entire length of said retainers being substantially in a single plane, and holding means for 30 said wires comprising transversely extending

members passing through the groove in said bar and disposed to pass within the loop portion of said wires.

3. A thread guide for textile machines comprising in combination a traverse bar having a narrow vertical groove extending longitudinally therein, thread guides resting on said bar, wire retainers for said guides having a looped central portion therein entering said slot and the end portions thereof resiliently engaging over the upper surfaces of said guides, the entire length of said retainers being in a single plane, and holding means for said wires comprising transversely extending members passing through said bar and intercepting said slot within said loops, whereby 15 said wire will be retained in position within said slot and will be free to angularly adjust itself while being retained in a vertical plane.

4. A retainer for thread guides comprising in combination a traverse bar having a longitudinal groove formed therein, thread guides mounted thereon, a wire having a central loop adapted to fit closely within the groove in said bar, oppositely extending resilient portions of said wire having their ends engaging over the upper surfaces 25 of and holding adjacent guides against said bar, the loop and end portions of said wire being in a single plane, and a transverse screw intercepting said groove and passing through said loop, whereby said wire is retained in position. 30
